CLAIM

The ornamental design for an air conditioner operation panel, as shown and described.

DESCRIPTION

FIG. 1 is a front elevational view of an air conditioner operation panel, showing our new design;
FIG. 2 is a rear elevational view thereof;
FIG. 3 is a top plan view thereof;
FIG. 4 is a bottom plan view thereof;
FIG. 5 is a right side elevational view thereof;
FIG. 6 is a left side elevational view thereof, and,
FIG. 7 is a front, top, and right side perspective view thereof.
The broken lines shown in the figures are for the purpose of illustrating portions of the air conditioner operation panel that form no part of the claimed design.

1 Claim, 6 Drawing Sheets
